(57) **CLAIM**

The ornamental design for a base stand for sensor bar, as shown and described.

DESCRIPTION

FIG. 1 is a front, top and right perspective view of a base stand for sensor bar showing our new design;

FIG. 2 is a rear, bottom and left perspective view thereof;

FIG. 3 is a right side view thereof, a left side view being a mirror image thereof;

FIG. 4 is a front view thereof;

FIG. 5 is a rear view thereof;

FIG. 6 is a top plan view thereof; and,

FIG. 7 is a bottom plan view thereof.
